ATTORNEY

UNITED STATES PATENT OFFICE.

CAY P. BUHL, OF PASSAIC, NEW JERSEY.

CARBURETER.

1,397,500.

Specification of Letters Patent. Patented Nov. 22, 1921.

Application filed January 24, 1920. Serial No. 353,715.

To all whom it may concern:

Be it known that I, CAY P. BUHL, a citizen of the United States, residing at Passaic, in the county of Passaic and State of New Jersey, have invented certain new and useful Improvements in Carbureters, of which the following is a specification.

This invention relates to carbureters for internal combustion engines, and it consists 10 in a novel combination of parts in that class of carbureters wherein relative movement is provided for as between the members forming the delivery nozzle and venturi throat, the invention having in view to increase the 15 efficiency of such carbureters and to render them more compact and adapted to have the movement of the one of said members that is shiftable capable of being effected with greater ease and with the use of simpler 20 instrumentalities than heretofore.

In the accompanying drawing,

Figure 1 is a side elevation of the carbureter, with the cover and the nearer sections of the throttle and throat members removed; 25 Fig. 2 is a vertical sectional view thereof; Fig. 3 is a plan;

Fig. 4 is an elevation of the throttle device and certain accessories, shown partly in section; 30 Fig. 5 is a side elevation of said device; and

Figs. 6 and 7 are opposite elevations of the throat member.

The substantially cylindrical casing 1, provided at one side with a removable cover 2, has opposite radial openings 3 and 4 forming its air intake and outlet, respectively; and it also has an opening 5 in which is suitably secured, largely housed within the 40 casing, the float chamber 6 to which the liquid fuel is admitted by the inlet 7 and from which it is delivered by the tubular projection or pipe 8 reaching across the mixing passage 1' of casing 1, said float chamber 45 containing any well-known constant-level-maintaining means, as float 9 and valve 10 for inlet 7 connected with said float by the lever 11.

Pipe 8, which is arranged horizontally 50 (the installed position of the carbureter being such that outlet 4 will be at the top), has an upwardly flaring mouth-piece 12, whose lip 13 is beveled or reduced all around to a thin edge. The mouth-piece receives 55 a member 14 formed with an underneath cavity 15 and, in the cavity, with a central boss

16, the margin of said member being beveled underneath and at the outside to form an exterior marginal surface parallel with the surrounding inner marginal conical surface 60 of lip 13. Parts 12 and 14 form a nozzle of the type which delivers fluid in a hollow cone, and the continuous conical outlet thereof formed by the aforesaid opposed marginal conical surfaces of said parts may be varied 65 by turning screw 17 tapped in member 14 and having its head projecting down through and obtaining an exterior bearing on pipe 8, member 14 being upheld by a spring 18 and guided vertically by having 70 its boss 16 telescoped with the tubular portion 19 of part 12, which has fluid passages at 19'. Access may be had to screw 17, for adjusting it, through a hole in the casing normally closed by a screw-plug 17' (Fig. 2). 75

The exterior form of the nozzle is substantially ovoid with the more rounded end downward, the upper or less rounded end being preferably reduced to a point; and preferably the fluid outlet of the nozzle is 80 substantially coincident with its maximum transverse diameter, as shown.

There is a manually shiftable control member which includes a throttle and a throat-forming device. The throttle device shown 85 is of the double-throttle type and comprises two flat side walls 21 joined by valves or throttles proper 22, 23, which form opposite segments of the same cylinder, and a radial wall or baffle 24 extending to the rearward 90 edge of throttle proper 23. A hub 25 projects outwardly from one wall 21, and a shaft 26, penetrating this hub and the other wall 21, projects outwardly from the latter wall. The hub and the relatively opposite 95 end of the shaft, both of which thus project from the walls 21, are journaled in hubs 2' formed on the cover 2 and the opposite wall of the casing (the latter wall being omitted in Fig. 4). The throttle device and shaft 100 normally rotate as one, though the former is adjustable relatively to the latter, as will appear. The throat-forming device is a sector-shaped block 27 having formed there-through from one radial face to the other 105 a throat 27' which is tapered and is further curved around shaft 26; said device is pinned on the shaft, being arranged between the walls 21 of the throttle device with the larger end of its throat downward as the parts are 110 seen in Fig. 2. The purpose of the relative adjustment, rotatively, of the shaft and

throttle device is to alter, rotatively, the positions of the throttle and throat-forming devices relatively to each other. For effecting this adjustment (while normally preserving the parts fixed with reference to each other) a worm-wheel 28 is fixed on the hub 25 and a yoke 31 is fixed on the shaft, the yoke having journaled therein a worm 29 engaging the worm-wheel and equipped with a milled nut 30 for turning it. The control member may be shifted back and forth by any suitable means, as a crank (not shown), attached to the left-hand end of the shaft 26 in Fig. 4; when the control member is shifted so that the throttles 22, 23 more or less close the openings 3, 4 there results a corresponding restriction of the passage formed around the nozzle within the throat, due to the taper of the latter. Both the throttle and throat-forming devices are shown made in two sections to permit assembling them. The end portion of shaft 26 which projects to the left in Fig. 4 is enlarged slightly and bears against the left-hand section of the throttle device. Having introduced the shaft through this section, then through the throat member, and then through the other section of the throttle device, and having pinned the throat member to the shaft, these parts are introduced into casing 1 so that said end of the shaft is journaled in casing hub 2'. Then the cover 2 is applied, leaving hub 25 journaled in cover hub 2'. Finally the worm-wheel and yoke 31 are fixed on the hub 25 and shaft 26, respectively. There is a pin 23' on the left-hand section 23 engaging a suitable hole—not shown—in the other section to lock the former to the latter for rotation therewith. The curved outer surfaces of the valves or throttles proper 22, 23 and the throat-forming device bear face to face against the inner surface of the cylindrical wall of the casing.

When the throttle device is in the position shown in Fig. 1 it fully closes the intake 3; but at that time a notch 32 in throttle proper 23 permits the engine suction to produce a

copious flow at the nozzle, atmospheric air being then admitted to chamber 6 through an orifice 33 (Fig. 2).

The members 12—14 and 27 together produce a throat forming means in which one is movable lengthwise of the axis of the throat to vary the volume of fluid adapted to pass therethrough, due to the taper of the throat. I have obtained compactness of structure, facility of movement of the moving part and simplicity of the instrumentalities for actuating said part because the movement is pivotal rather than rectilineal. Noise and undue turbulence of the air passing through the throat is reduced because the nozzle is substantially ovoid in form and has its smaller end projecting relatively toward the outlet of the throat, and notwithstanding the curvature of the throat such nozzle makes the throat one of the venturi class and on account of its peculiar form, taken with the curvature of the throat, causes the zone of greatest restriction of the venturi to be disposed desirably above the annular fuel outlet of the nozzle; this zone of greatest restriction of the venturi, it will be seen, is substantially contiguous to the inclined plane represented by the upper face of the member 27 in the position of said member illustrated in Fig. 1.

Having thus fully described my invention, what I claim as new and desire to secure by Letters Patent is:—

A carbureter venturi means including a throat-forming member and a substantially ovoid air-flow obstructing member arranged in the throat of the first member and spaced therefrom, one of said members being shiftable relatively to the other in a path curved around an axis transverse to and exterior of the throat and the throat being tapered and curved around said axis, the obstructing member having its smaller end projecting toward the smaller end of the throat.

In testimony whereof I affix my signature.

CAY P. BUHL.
